UNITED STATES PATENT OFFICE.

EMIL PODSZUS, OF FRIEDRICHSHAGEN-BERLIN, GERMANY, ASSIGNOR TO SIEMENS & HALSKE AKTIENGESELLSCHAFT, OF SIEMENSSTADT, NEAR BERLIN, GERMANY, A CORPORATION OF GERMANY.

PRODUCTION OF LIGHT BY ELECTRICITY.

Application filed September 2, 1921, Serial No. 498,173, and in Germany July 26, 1918.

My invention refers to the production of light by electricity and more especially to lighting devices producing light by the passage of the electric current through vapours capable, on being raised to a sufficiently high temperature, of emitting luminous rays, such as metal vapours and more especially mercury vapour or the vapours of metal compounds such as compounds of the earth 5 alkalies or the rare earths.

The particular effect of the so-called flame arc lamps is based mainly on the luminosity of such vapours heated by the electric current. However the practical effects obtained with such lamps remain far below 15 the theoretical maximum.

I have ascertained in the course of extensive investigations, that in order to improve the efficiency of such lamps, it is important 20 to raise the intensity of the current and the current density in that part of the incandescent vapor which conducts the current, up to a certain amount.

I have further ascertained that the minimum amount to which the density must be raised depends upon the strength of the current, inasmuch as the product of strength of current in amperes and of the current density in amperes per square 25 millimeter should be at least 50. In consequence thereof, assuming the strength of current to be 50 amperes, the current density should be equal to at least 1 ampere per square millimeter of the sectional area of 30 the vapour column effectively conducting the current.

In order to obtain such a high current density and at the same time to restrain as far as possible the detrimental absorption of 40 light in the cooler layers of the vapour, it is imperative, instead of allowing the vapour to spread freely, as has been the case hitherto, to concentrate it within a tubular sleeve and to conduct it therein at least for that 45 portion of its path where the production of light takes place. This sleeve should be so dimensioned that the sectional area of the vapour column enclosed therein answers the condition mentioned above insofar as the 50 sectional area in square millimeters does not exceed the fiftieth part of the square of the strength of current in amperes. Care should be taken at the same time to make

the sleeve long enough, the whole arrangement being such that the vapour column 55 within the sleeve is utilized as perfectly as possible for the conduction of the current.

One may as well employ a magnetic guide or enclosure, masses of iron and current carrying conductors they being arranged in 60 such a manner that the lines of current are crowded together on a narrow space.

In the drawings affixed to this specification and forming a part thereof an arc lamp in accordance with the present invention is 65 illustrated,

Fig. 1 is a diagrammatic longitudinal section, and

Fig. 2 is a similar section of a modification, the non-essential parts being broken 70 away and being assumed for the present purpose to be substantially similar to those shown in Fig. 1.

Referring to Fig. 1 of the drawings, *a* is the electrode generating the vapour column 75 and *b* is a coil enclosing that part of the electrode which is nearest to the arc, an insulating sleeve 11 being inserted between them. *c* is a tubular iron core dimensioned in accordance with the size of the arc in such a 80 manner that the path of the arc is closely surrounded by a powerful parallel magnetic field in tubular fashion, while within the arc this field is very weak. The opposite electrode *d* is provided with a current carrying coil *e*, wound in such a direction that the magnetic polarity of its end facing the 85 arc is opposite to that existing at the arc end of coil *b* of the other electrode. By these means an effective counter pole for the 90 tubular magnetic field is formed. 2, 2 are rings for feeding the electrodes with current, 3 is a source of electricity furnishing current to the electrodes as well as to the motor 4 serving to advance them by aid of 95 bevel gears 5 and worm gear 6. A worm shaft 7 driven from bevel gears 6 drives in its turn a pair of worm wheels 8, 8 disposed above and below the rear end of electrode *a* on axles 9, 9 crossing each other at a pointed 100 angle and carrying friction rollers 10, 10 in frictional contact with the electrode. Owing to the worm wheels 8, 8 being disposed on the same side of the worm shaft 7 the rollers 10, 10 revolve in the same direction and cause the electrode *a* to turn 105

around its axis. Owing to the roller axles 9 being disposed at an angle to each other the rollers at the same time impart to the electrode a slow advancing motion.

5. 12 is a shaft revolved by worm gear 6 and 13 is a roller on said shaft in frictional contact with the counter electrode *d* and advancing same.

10. 24 is a tubular element within which one of the electrodes, in this case 23, is disposed. This sleeve which does not partake in the conduction of current may consist, as shown in Fig. 1, of refractory non-conducting material. Furthermore, while operating in 15. Fig. 1 in conjunction with the magnetic means for closely confining the arc, this sleeve in some instances may form itself already a sufficiently effective means for that purpose without making use of the magnetic 20. means, for instance in Fig. 1 without exciting the magnet coil *b*.

25. In order to obtain the highest possible intrinsic brilliancy the concentration of the luminous vapour should be chosen as high as possible and therefore all diluting gases and vapours having an unfavorable emission, such as carbon vapour, should be kept away from the zone of incandescence. One should avoid employing carbon electrodes 30. under conditions, fostering the generation of any appreciable quantities of carbon vapour which might be introduced into the zone of incandescence. In case the tube 24 is made of conducting material, as shown for 35. instance in Fig. 2, I have found carbon to be very satisfactory. By suitable means, described below, such a carbon tube is prevented from emitting carbon vapours, so that the incandescent zone is kept free from 40. such vapours.

45. In all those cases where it is of importance to protect the sleeve against the effects of the very high temperature I prefer employing a special cooler which may be a water jacket such as shown in Figs. 1 and 2 of the drawings where 14 is the cooler consisting of a jacket preferably made of copper or another metal of superior heat-conductivity, fed with water and insulated from, but 50. closely surrounding the sleeve. This jacket should conduct the water close up to the mouth of the sleeve and the water feed should be controlled in such a manner that the great quantities of heat evolved are carried away before steam can form.

55. The vapour used may either be introduced into the sleeve in any suitable manner or it may be generated therein. I may for instance introduce mercury vapor into the 60. sleeve from the rear as shown in Fig. 2, where *a* is the electrode, *o* is the sleeve and *x* is the mercury inlet. In general the vapour contained within the sleeve will slowly escape therefrom when the lamp is working 65. and it is therefore necessary to replace the

lost quantity of vapour. This can be effected by suitably introducing a uniform jet of vapour through pipe *x*.

With the arrangements described above an exceedingly high light efficiency approaching very nearly the theoretic maximum can be obtained. At the same time there results an extraordinary increase of light intensity per unit of area of the source of light. These advantages are of the greatest importance in search lights and an almost point source of light is obtained even with very high currents.

I claim:

1. In an electric lighting device in combination, a pair of solid electrodes, means for forming an electric arc between said electrodes, means for producing light emitting vapours for feeding the arc formed between said solid electrodes and a rigid cooling device for restricting the cross section of at least a portion of the arc vapour column to approximately the cross section of one of the electrodes to prevent its spreading for the purpose set forth.

2. In an electric lighting device in combination, a pair of solid electrodes, means for forming an electric arc between said electrodes, means for producing light emitting vapours for feeding the arc formed between said solid electrodes and a tubular sleeve around a part of the vapour column formed between said electrodes, said sleeve having an inner diameter approximately equal to that of one of the electrodes.

3. In an electric lighting device in combination, a pair of solid electrodes, means for forming an electric arc between said electrodes, means for producing light emitting vapours for feeding the arc formed between said solid electrodes and a highly refractory tube placed around a part of the vapour column formed between said electrodes, said tube having an inner diameter approximately equal to the diameter of one of the electrodes.

4. In an electric lighting device in combination, a pair of solid electrodes, means for forming an electric arc between said electrodes, means for producing light emitting vapours for feeding the arc formed between said solid electrodes and a carbon tube around a part of the vapour column formed between said electrodes.

5. In an electric lighting device in combination, a pair of solid electrodes, means for forming an electric arc between said electrodes, means for producing light emitting vapours for feeding the arc formed between said solid electrodes, an enclosure around a part of the vapour column formed between said electrodes for restricting the cross section of said column substantially to that of one of the electrodes and means for cooling said enclosure.

6. In an electric lighting device in combination, a pair of solid electrodes, means for forming an electric arc between said electrodes, means for producing light emitting vapours for feeding the arc formed between said solid electrodes and a tubular sleeve around a part of the vapour column formed

between said electrodes, said sleeve having an inner diameter substantially equal to that of one of the electrodes and means for cooling said tubular sleeve. 10

In testimony whereof I affix my signature.

EMIL PODSZUS.
